UNITED STATES PATENT OFFICE.

THOMAS W. ROLPH AND WILLIAM FROST MINOR, OF CLEVELAND, OHIO, ASSIGNEES TO
GENERAL ELECTRIC COMPANY, A CORPORATION OF NEW YORK.

LIGHTING-FIXTURE.

1,304,378.

Specification of Letters Patent. Patented May 20, 1919.

Application filed May 16, 1916. Serial No. 97,799.

To all whom it may concern:

Be it known that we, THOMAS W. ROLPH and WILLIAM FROST MINOR, citizens of the United States, both residing at Cleveland, 5 county of Cuyahoga, State of Ohio, have invented certain new and useful Improvements in Lighting-Fixtures, of which the following is a specification.

Our invention relates to a totally inclosed 10 electric light fixture particularly adapted to the housing of a high efficiency tungsten lamp.

The direct rays from a concentrated source of light, as the high efficiency tungsten lamp, 15 are highly intense and discomforting to the eyes. One object of our invention is to avoid all glare by diffusing and softening or totally shielding these direct rays without at the same time impairing the efficiency of the 20 transmission and distribution of the light as a whole, and we accomplish this by incorporating in the globe and interposing in the path of the rays which ordinarily strike the eye a diffusing or softening glass, the other 25 parts of the globe preferably being of a glass less dense and more transparent for efficiently transmitting the light to the areas to be illuminated. More specifically, our 30 globe embodies three distinct and separate parts, all fitting into each other to form a totally inclosed globe with zones of glass varying in density. The middle section or 35 zone is of sufficient density to soften and diffuse the direct rays comfortably to the eyes, while the lower section and the upper section are preferably more transparent for 40 efficiently illuminating wide areas both below and above the fixture.

The multipart or zone feature of our globe 45 is important in contributing to easy assembly, the various sections being readily brought together to form a dust proof enclosure. Sections of different designs may be provided and easily substituted to change 50 the appearance of the globe, and the globe as a whole is not rendered useless by the breaking of a section, inasmuch as the broken zone may be replaced by a new one with facility.

55 The preferred embodiment of our invention is illustrated in the drawing accompanying this specification, wherein a high efficiency tungsten lamp 1 is shown as housed in our improved inclosure. The lamp socket is illustrated as fitting in the usual manner

to the neck of the upper part or dome 2 of our globe. The middle section or zone 3 has on its upper periphery an annular groove for receiving in a dust proof manner the skirt of the dome 2 and the ring 4 is attached 60 to the upper edge of the middle section, being supported from the ceiling by chains 6. Before the parts 2 and 3 are assembled, however, a bowl 5 is lowered through the top of zone 3 into engagement with the lower periphery, an annular curved bearing surface on the zone coöperating with a similar surface on the rim of the bowl to form a dust proof joint.

The density of the glass of zone 3 should 70 be sufficient to comfortably diffuse and soften the rays passing therethrough, and the zone should be wide enough and of a conformation to intercept the rays that ordinarily strike the eye of an observer in approaching. With the particular dimensions and shape illustrated, these softened and subdued rays are embraced within the angle A—B—C, the angle of the diffused light below the horizontal plane passing through B 80 being greater than that above the plane. This particular arrangement lends itself to a proper distribution of the light as a whole, the dome 2 and bowl 5 preferably being of a glass of lower density and more transparent 85 than zone 3 for freely transmitting the light in the upward and downward directions.

What we claim and desire to secure by Letters Patent of the United States, is:

1. An outer globe particularly adapted 90 for housing a high efficiency tungsten lamp comprising a lower section and an upper section in combination with a middle section extending from the lower edge of said upper section to the upper edge of said 95 lower section and composed of a denser and less transparent medium than either of the other sections.

2. An outer globe particularly adapted 100 for housing a high efficiency tungsten lamp comprising a dome section, a bowl section and an intermediate section extending from the lower edge of said dome section to the upper edge of said bowl section and composed of a denser and less transparent medium than either of the other sections.

3. An outer protective and light distributing globe particularly adapted for housing a high efficiency tungsten lamp comprising a transparent dome, a transparent 110

bowl, and a middle zone of a softening and diffusing glass, the three sections fitting into each other to form a totally inclosing globe.

4. In a lighting fixture, the combination
5 of a high efficiency tungsten lamp with a three part totally inclosed globe comprising a transparent dome, a transparent bowl, and a middle translucent zone bridging the rim of the bowl and the skirt of the dome.
- 10 5. An outer protective and light distributing globe particularly adapted for hous-

ing a high efficiency tungsten lamp comprising a middle zone of a diffusing glass with means for suspending same in combination with a bowl and a dome carried by and fitting into said middle zone to form a totally inclosing globe.

In witness whereof, we have hereunto set our hands this 11th day of May, 1916.

THOMAS W. ROLPH.
WILLIAM FROST MINOR.
